UNITED STATES PATENT OFFICE.

JOHN W. STALDER, OF LINCOLN, NEBRASKA.

RAILWAY TIE.

Application filed October 5, 1923. Serial No. 666,763.

To all whom it may concern:

Be it known that I, JOHN W. STALDER, a citizen of the United States, residing at Lincoln, in the county of Lancaster and State of Nebraska, have invented new and useful Improvements in Railway Ties, of which the following is a specification.

The object of my said invention is the provision of a railway tie or sleeper peculiarly adapted to adequately support the rails of a railway while precluding lateral deflection of the railway and spreading of the rails or movement of either rail relative to the other.

To the attainment of the foregoing, the invention consists in the improvement as hereinafter described and definitely claimed.

In the accompanying drawings, forming part of this specification:—

Figure 1 is a top plan view showing one of my novel ties as incorporated in a railway.

Figure 2 shows one of the rails in side elevation and the tie in end elevation.

Figure 3 is an inverted plan view of the portion of railway embodying the tie.

Figure 4 is a vertical section on line 4—4 of Figure 1.

Figure 5 is a vertical section taken in the plane indicated by the line 5—5 of Figure 1.

Fig. 6 is a perspective of one of the I-form blocks.

The illustrated rails 1 are of ordinary construction, and are superimposed on and connected to the tie. At this point I would have it understood that it is within the purview of my invention to make the elements of my novel tie of any material or materials compatible with the purpose of the tie.

By comparison of the several figures of the drawings, it will be understood that among other elements the tie comprises three longitudinally disposed and spaced triangular members 2, arranged with their apices downwardly. Two of these members 2 are disposed under the rails, and it will be manifest that all of the said members 2 will have a tendency to settle in ballast and will serve efficiently in preventing lateral shifting or casual movement of the railway relative to the ballast. In the upper edges of the members 2 are recesses 3. These recesses 3 are designed to snugly receive a transverse channeled member 4 which serves as hereinafter set forth as one of the means for holding the members 2 against lateral movement

with respect to each other. It will be noticed, however, that the members 2 are also connected together by rods 5 which extend through and are appropriately connected to the said members 2. Said connection may be effected in any ordinary or approved manner. The transverse channeled member is provided at opposite sides of each of the triangular members 2 with upright ribs 6, 65 which bear against opposite sides of the triangular members 2 and thereby preclude endwise shifting of the members 4 through the said triangular members 2. The upper sides of the triangular members 2 and the upper side of the transverse channeled member 4 are preferably flush as shown. It will also be noticed that the channeled member 4 is provided with a longitudinal opening in its upper wall, said opening being designated by 7, and being arranged between pendent longitudinal flanges 8 on the upper walls of the member 4. Sheathed in the end portions of the channeled member 4 are blocks 9 of I-form in cross-section and arranged with their webs horizontally. These blocks 9 serve for the connection of upstanding threaded bolts 10, which extend through the webs of the blocks and have their heads 11 seated and held against rotation in the lower channels of the blocks. The said bolts 10 also extend upwardly through rail clamps 12 which rest over the outer portions of the bases of the rails and are provided with pendent flanges 13 disposed in the longitudinal opening 7 of the member 4 and are secured on the bolts 10 by nuts 14. In this connection it will be noted that when the nuts 14 are tightened, the I-blocks 9 and the rail clamps 12 will be strongly clamped against the channeled member 4 with the result that there is no liability of the rail clamps moving outwardly relative to the channeled member 4. Fixed in the intermediate portion of the longitudinal opening 7 in the upper side of the channeled member 4 is an intermediate bar 15, and appropriately fixed to the channeled member 4 outwardly beyond the ends of the intermediate bar 15 are upstanding bolts 16. These bolts 16 extend through and serve for the connection of the inner rail clamps 17 which clamps 17 have pendent flanges 18 disposed in the longitudinal opening 7 and are secured by nuts 19 on the bolts 16 so as to rest over and hold the inner portions of the rail bases. It will be no-

ticed that the said flanges 18 of the inner clamps 17 abut against the ends of the intermediate bar 15, and hence said intermediate bar 15 is adapted to preclude movement of the inner rail clamps 17 toward each other. In this connection it will be apparent that it is within the purview of my invention to channel the end portions only of the bar 4, in which event the portion designated as the intermediate bar 15 will be made integral with the channeled bar 4.

It will be apparent from the foregoing that without being unduly expensive my 15 novel tie is adapted to adequately support and strongly hold rails in such manner that there is no liability of either rail moving laterally relative to the other, and no liability of the rails and tie shifting laterally in 20 the ballast ordinarily employed in railway construction. It will also be appreciated that the channeled member 4 is adapted to be seated in ballast with a view of effectively preventing shifting of the tie in the 25 direction of the length of the railway.

I have entered into a detailed description of the construction and relative arrangement of the parts embraced in the present and preferred embodiment of my invention in 30 order to impart a full, clear and exact understanding of the said embodiment. I do not desire, however, to be understood as confining myself to the specific construction and relative arrangement of parts inasmuch as 35 in the future practice of the invention various changes and modifications may be made such as fall within the scope of my invention as defined in my appended claims.

Having described my invention, what I 40 claim and desire to secure by Letters Patent, is:—

1. A railway tie comprising triangular members arranged longitudinally of the track and spaced apart and also arranged 45 with apices lowermost, said members having recesses in their upper sides, transverse rods connecting the said triangular members together, a transverse member seated in the recesses of the triangular members and having exterior upstanding ribs at opposite 50 sides of the triangular members and also having channeled portions at its ends and longitudinal openings in the tops of its end portions and flanges depending from said tops at opposite sides of said openings, I-blocks sheathed in the end portions of the transverse member and arranged with their webs horizontal, bolts fixed to the transverse member and extending upwardly through 55 the longitudinal openings in the top thereof at points between the rail supporting portions of the tie, inner rail clamps mounted on said bolts and having pendent flanges in said openings and abutting against the intermediate top portion of the transverse member; the said longitudinal openings of the transverse member, outer 60 transverse rail clamps mounted on said bolts and having pendent flanges disposed in the longitudinal openings of the transverse member, and nuts mounted on the said bolts and disposed above the outer rail clamps, the two outer triangular members of the tie being adapted to rest under and in vertical alinement with rails when rails are superimposed on the transverse member and are secured between the inner and outer rail clamps.

member, nuts mounted on said bolts and disposed above said inner rail clamps, bolts extending upwardly through the webs of the I-blocks and also through the longitudinal openings of the transverse member, outer 70 transverse rail clamps mounted on said bolts and having pendent flanges disposed in the longitudinal openings of the transverse member, and nuts mounted on the said bolts and disposed above the outer rail clamps. 75

2. A railway tie comprising triangular members arranged longitudinally of the track and spaced apart and also arranged with apices lowermost, said members having recesses in their upper sides, transverse rods 80 connecting the said triangular members together, a transverse member seated in the recesses of the triangular members and having exterior upstanding ribs at opposite sides of the triangular members and also 85 having channeled portions at its ends and longitudinal openings in the tops of its end portions and flanges depending from said tops at opposite sides of said openings, I-blocks sheathed in the end portions of the 90 transverse member and arranged with their webs horizontal, bolts fixed to the transverse member and extending upwardly through the longitudinal openings in the top thereof at points between the rail supporting portions of the tie, inner rail clamps mounted on said bolts and having pendent flanges in said openings and abutting against the intermediate top portion of the transverse member; the said longitudinal openings of the transverse member, outer 95 transverse rail clamps mounted on said bolts and having pendent flanges disposed in the longitudinal openings of the transverse member, and nuts mounted on the said bolts and disposed above the outer rail clamps, the two outer triangular members of the tie being adapted to rest under and in vertical alinement with rails when rails are superimposed on the transverse member and are secured between the inner and outer rail 100 clamps.

3. A railway tie comprising spaced longitudinal members adapted to be embedded in ballast, a transverse member seated in said longitudinal members and having projections at opposite sides of said longitudinal members to prevent lateral movement thereof relative to the transverse member, and inner and outer rail clamps connected to the transverse member; the said longitudinal members having pointed portions extending below the horizontal plane of the transverse member.

4. A railway tie comprising spaced longitudinal members adapted to be embedded in ballast, a transverse member seated in said 110

longitudinal members and having projections at opposite sides of said longitudinal members to prevent lateral movement thereof relative to the transverse members, and
5 inner and outer rail clamps connected to the transverse member, the connections of the outer rail clamps including blocks sheathed in the end portions of the transverse mem-

ber and having recesses in their undersides, and bolts extending upwardly through said 10 blocks and also through the outer rail clamps and having heads disposed in and held against turning by said recesses of the blocks.

In testimony whereof I affix my signature.

JOHN W. STALDER.
